UNITED STATES PATENT OFFICE

EDWARD O. BRAATEN AND OTTO R. HARMER, OF NORTHFIELD, MINNESOTA

STORM WINDOW OPENING AND CLOSING DEVICE

Application filed March 24, 1930. Serial No. 438,366.

Our invention relates to storm window brackets in general and more particularly to a simple, inexpensive and efficient device for automatically opening a storm window or closing same according to the movement of the slideable sash of the window structure to which the storm window is hingedly suspended at its upper part.

The advantages, simplicity and operation of our device are hereinafter fully set forth, reference being had to the accompanying drawings, in which,—

Fig. 1 is a vertical sectional elevation of a window frame including its storm sash and one of our storm sash manipulating devices in operative position.

Fig. 2 is an enlarged sectional view as on line 2—2 in Fig. 1, at the right hand side of the window and omitting the storm sash.

Fig. 3 is an enlarged detail view on a slightly lower level than Fig. 2; namely, about as on line 3—3, and showing mainly the manipulator rod guide of our device in operative position on the side bar of the storm window.

Referring to the drawings by reference numerals, 5 designates the window sill, 6 the vertical side member of a window frame (right side only illustrated). In said side member is fixed the usual parting strip 7, shown integral with 6 in Figs. 2 and 3, and against the forward edges of which a storm window 8 bears when in closed position (see Figs. 1 and 3). Inwardly of strip 7 the usual upper window sash 9 and lower sash 10 are mounted slidably in the frame in any suitable manner and as is well known in the building industry.

We have shown only one of our storm window devices as applied to one side of a storm window, it being understood that a pair of the devices are required for each such window, such pairs being counterparts and a description of the one shown being sufficient for both.

Each device comprises a main manipulated bar of elongated reversed S-shape bar 11, pivotally secured to strip 7 of the window frame at a predetermined elevation, as at 12 in Fig. 1. From thence the bar extends in

wardly and downwardly in a curvature designated 11A (Fig. 1) thence extending preferably straight but in an incline forwardly toward the storm window, as 11B (Fig. 1) and its lower part arched inwardly as 11C, in reverse curvature to part 11A. When the storm window is closed the bar 11 occupies a space below sash 9 between the storm window and the inner sash but not obstructive to movement of the inner sash 10.

13 is an eye-screw with an elongated eye 13E to slidably receive the bar 11, said screw being fixed in the side bar 8' of the storm sash at a predetermined height and engaging the bar 11 near its lower end when the storm sash is closed. 14 is an L-shaped bracket or angle iron, the base of which is secured to the side bar of the inner window sash 10, as at 15, with the main arm extending forward in vertical plane. The outer part of said main arm of bracket 14 carries a U-shaped member or clip 16, swiveled on a suitable pin 17 fixed in the bracket, said U-shaped part straddling the manipulator bar 11 (see Figs. 1 and 2). The bracket 14 is so located on the inner sash that the U-member 16 engages bar 11 and holds the storm window in closed position when the inner sash 10 is down.

Obviously when inner sash 10 is raised the U-member rides upwardly on the angular part 11B and the curvature 11A causing the storm sash to be forced outwardly gradually and according to the height said inner sash is raised. In Fig. 1 the bracket 14 is shown raised quite high (see dotted position) with the U-shaped clip 16 having forced bar 11 and storm sash 8 approximately to maximum outer position. The storm sash is of course suspended at its upper horizontal edge on suitable hinge means (not shown). The U-clip 16 has a constant sliding contact with bar 11. The eye-screw bar guide 13 is located so that any normal outward movement of the storm sash will not allow the bar 11 to slip out of it, but as a precaution to prevent this a light wire ring 18 may be inserted in the lower end of bar 11. When our storm window is put in place or is disconnected the ring 18 is simply removed temporarily and the lower end of bar 11 is insertible down-

wardly into guide 18 or removable upwardly out of it as the case may be.

It will be readily seen that our device embodies only a very few operating parts readily attached to windows of the class set forth, and its storm window opening and closing action is positive and according to vertical movement of the window sash. Large or small volume of air circulation is thus readily available for any room, as desired.

We claim:

1. An opening and closing device for hingedly suspended outer window sash normally in parallel relation to slidable sash, said devices comprising for each side of the window an irregularly curved, elongated actuating bar pivotally and freely suspended by its upper end from a pin fixed in the window frame parting strip between said outer and the sliding sash, a bracket fixed to the sliding sash and means thereon slidably engaging said actuator bar, guide member comprising an eye screw on the outer sash slidably engaged by the actuator bar, below said fixed bracket of the slidable window sash, said actuator bar below its pivot formed in an elongated S-shape, first an inwardly directed curvature then a straight part and its lower extremity formed in a curvature reverse of the first described curvature.
2. The structure specified in claim 1, and an actuating-bar engaging member on the said window bracket comprising a U-shaped clip straddling the actuator bar transversely and swivel mounted on the outer end part of said bracket.

In testimony whereof we affix our signatures.

EDWARD O. BRAATEN.
OTTO R. HARMER.
